INSTRUMENT CASING

Richard P. Brown, Philadelphia, Pa., assignor to
The Brown Instrument Company, Philadelphia, Pa., a corporation of Pennsylvania

Application October 24, 1931, Serial No. 570,809

5 Claims. (Cl. 73—151)

My present invention relates to the construction and mounting of the casings or housing elements of pressure gauges, gas and liquid actuated recording thermometers, flow meters and other measuring and exhibiting instruments which may serve a wide range of purposes.

One general object of my present invention is the provision of an instrument case adapted to be interchangeably mounted in different types of mountings. Another general object of the invention is to provide an instrument case of such construction as to facilitate the attachment thereto of means for closing openings in the casing through which a wire or conduit connection may be made between the mechanism within the casing and associated apparatus external of the casing in one or another different modes as the character of the mounting or the character of the mechanism enclosed within the casing may make desirable.

The various features of novelty which characterize my invention are pointed out with particularity in the claims annexed to and forming a part of this specification. For a better understanding of the invention, however, and the advantages possessed by it, reference should be had to the accompanying drawing and descriptive matter in which I have illustrated and described preferred embodiments of the invention.

30 Of the drawing:

Fig. 1 is a front elevation partly broken away of an instrument case mounted on a wall;

Fig. 2 is an elevation with parts broken away and in section of the instrument case shown in Fig. 1 as arranged in a flush panel mounting;

Fig. 3 is an enlarged rear view of a portion of the instrument case as arranged in Fig. 2;

Fig. 4 is a vertical section on the line 4—4 of Fig. 3; and

40 Fig. 5 is a view similar to Fig. 2 of a pipe mounting.

In the drawing I have illustrated the invention as embodied in an instrument case of circular outline, such as is used, for example, with a recording thermometer or pressure gauge having a disc-shaped record chart. The instrument case shown comprises a box-like body member A of circular cross-section and advantageously formed of die-cast aluminum. The body A is open at its front 45 to permit access to its interior when the door B, which is hinged to the body at B', is open. The door can be opened and closed by means of the knob B² arranged at one side thereof.

50 The body A is provided with a relatively narrow externally projecting flange A' at the margin of

the door opening. When the instrument case is mounted flush with a vertically disposed panel board C, as shown in Fig. 2, the body extends through a circular opening C' in the panel C, and the rear side of the marginal flange A' contacts 60 with the front side of the panel at the margin of the opening C' therein. When so arranged, the case is clamped in position by means of a series of clamping members D secured to the panel by screws D' and gripping the marginal flange A' 65 at circumferentially spaced points.

When the instrument case is desired to be mounted on a vertical wall E, as shown in Fig. 1, it can be secured thereon by means of flat elongated lugs F arranged in shallow grooves or 70 pockets A² formed in angularly spaced marginal portions of the rear wall A³ of the body at the rear side thereof and secured thereto by screws F' tapped into thickened parts A⁴ of the rear wall 75 portions forming the bottoms of the grooves A². The opposite end portion of each lug is formed with an opening F², adapted to receive a screw G for securing it to the wall. The lugs and grooves are advantageously so relatively proportioned 80 that each lug may be secured in the corresponding groove with either of its ends outermost. When the case is to be connected to a wall, the lugs are arranged with the ends containing the opening F² outermost and projecting beyond the periphery of the body, as shown in Fig. 1. When 85 the case is to be flush mounted, the lugs are turned from their projecting position indicated by full lines in Fig. 1 and broken lines in Fig. 2 to their concealed position shown by full lines in Fig. 2. In the latter position, the lugs will be flush with 90 the rear side of the body rear wall and with the peripheral wall A⁵.

The receiving and exhibiting mechanisms housed in the instrument case when the latter is installed must usually be connected to associated 95 apparatus located externally of the case. Connectors for this purpose are usually passed through one or more openings formed in one of the body walls at a point accessible to the user. For example the most suitable location for the connector opening for a wall mounted instrument case has been found to be in the exposed peripheral wall A⁵ of the body, and in a flush type 100 mounting in the rear wall A³, since in the latter type most of the peripheral wall is concealed by 105 the supporting panel structure.

In accordance with the invention, an instrument case of the character described is also provided with a special body wall opening or openings in which a special closure attachment part 110

or parts may be interchangeably positioned to permit external connectors to pass into the case at the most suitable point for each type of mounting, while in all mountings the case is maintained closed to prevent the entrance of dust, dirt or fumes with consequent injury to the enclosed mechanism. As shown, the lower portion of the peripheral wall A⁵ is formed with a rectangular opening A⁶ extending from a point near, but spaced from, the rear side of the marginal flange A' to the rear edge thereof. The adjoining portion of the rear wall is formed with a similarly shaped opening A⁷, the side edge portions of which are in alignment with the corresponding edge portions of the peripheral wall opening A⁶ and form continuations thereof. The marginal portions of the openings A⁶ and A⁷ are similarly cut away at their outer sides to form relatively narrow ledges or seats A⁸ and A⁹, respectively, on which the closure part or parts hereinafter described are seated and secured.

In accordance with my invention, the opening so formed in the rear corner of the case is closed by one or more closure members adapted to be interchangeably positioned therein, said closure members, or at least one of them, being provided with means permitting the connection thereto of an external part. As shown in Figs. 1-4, two such closure parts are employed, one of which is a rectangular plate H, which is adapted to be positioned over either of the body opening portions with its side edge portions abutting the ledges A⁸ or A⁹ and secured thereto by flat headed screws H'. The other closure member is a plug J, also of rectangular formation, but of greater thickness than the plate H. A projecting marginal flange J' is formed at the outer side of the plug J to abut the marginal ledges A⁹, to which the side portions of the flange are secured by flat headed screws J². The main portion of the plug extends through the wall opening A⁷ into the interior of the instrument case.

The main portion of the plug J is formed with a central passage J³ having a rectangular countersunk outer end portion J⁴ and through which extends the terminal head K of a conduit member M. The head K is of tubular formation to permit the passage therethrough of a connector N carried in the member M. The connector N may be in the form of electrical conductors, a capillary tube, or a continuation of the conduit member M, depending upon the character of the measuring instrumentalities employed. The head K is proportioned to snugly fit in the plug passage J³ and is held in position therein in any suitable manner, such as by a leaf spring O interposed between the inner side of the plug K and a peripheral flange K' formed on the inner end of the head.

In mounting the instrument case, the connector-carrying plug J is fitted into the more suitable of the two wall openings and the closure of the case completed by the plate H. When a flush type mounting is used, the plug J is desirably arranged in the rear wall opening, as shown in Figs. 2-4. The peripheral wall opening will then be closed by the plate H. As shown in Fig. 4, the closure parts are so proportioned that the rear portion of the plate H combines with the lower flanged portion of the plug J to provide a tight joint therebetween and a smooth outer surface conforming with the remaining outer surface portions of the body. As shown in Fig. 3, the outer side of the plate H is flat to permit it to

conform with the rear wall of the body when closing the opening A⁷.

When the instrument case is to be mounted on the front of a wall E, as shown in Fig. 1, the plug J is positioned in the peripheral wall opening A⁶ and the plate H utilized to close the rear wall opening A⁷. In this arrangement the lower edge of the plate will contact with the then rear side of the plug body and upper face of the rear flanged portion to completely close the body of the case.

The closure parts H and J may thus be interchangeably positioned in the different portions of the case opening and the tap holes for the screws H' and J² in the ledges A⁸ and A⁹ and in the closure parts are advantageously similar in size and arrangement to permit interchangeable screws to be used. Tight joints between the closure parts may be further insured by providing the contacting surfaces of the closure parts and ledges with joint-sealing material, as indicated in the drawing.

Fig. 5 illustrates the use of the above described instrument case with a different form of closure means for the said openings A⁶ and A⁷. The closure means shown in Fig. 5 comprises an attachment of angle form having two integrally connected plate portions P' and P² extending transversely to one another and each shaped to fit against the seat associated with each opening. As shown the portion P' is formed with an opening P³ into which a pipe Q is secured as by a threaded connection. As shown in Fig. 5 the pipe Q extends downward, but by shifting the disposition of the part P so that the portion P² closes the bottom opening A⁶ while the part P' closes the rear wall opening A⁷, the pipe Q will then extend horizontally away from the rear wall of the casing. The pipe Q may form or surround a pressure transmitting conduit connection to the instrument mechanism within the casing, or may enclose a wire connection to said mechanism when this is desirable. In some cases the pipe Q may serve simply as a post forming the support, or one of the supports for the instrument.

The described instrument case construction eliminates any necessity for a special case form for each type of mounting and obviously results in lower manufacturing costs due to the reduction in case types required to be manufactured. The provisions by which this capacity for interchangeable use is attained do not increase the size or render the instrument unsightly and add little to the weight and cost of the individual cases. By the use of the interchangeable closure parts, the capacity for different types of mounting is increased and the effectiveness and appearance of the mounting is improved by the permissible location of the external connectors in the most advantageous position relative to the case.

While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention what I claim as new and desire to secure by Letters Patent, is

150

1. A casing for an instrument of the type specified comprising a box-like body open at its front side and formed with an opening in its rear wall and with an opening in its side wall merging with the rear wall opening at the corresponding portion of the casing and having similar seats associated with the two openings and an attachment part adapted to be interchangeably secured against each seat to close the corresponding opening. 5
2. A casing for an instrument of the type specified comprising a box-like body open at its front side and having communicating openings formed at the juncture of peripheral and rear wall portions thereof, a covering plate detachably arranged in one of said openings, and a connector-carrying plug detachably arranged in the other of said openings, said plate and plug being interchangeable in use and uniting to close said body openings. 10
3. A casing for an instrument of the type specified comprising a box-like body substantially circular in cross-section and open at its front side, said body having communicating openings formed at the juncture of peripheral and rear wall portions thereof, a covering plate having a flat outer surface, and a connector-carrying plug, said plate and plug each fitting interchangeably in each of said openings and uniting when one is in one, and the other is in the second of said openings, to close both openings. 15
4. A casing for an instrument of the type specified comprising a box-like body substantially circular in cross section and open at its front side, a marginal flange projecting a small distance outwardly from the peripheral wall of said body adjacent the front side thereof and adapted for connection to the marginal portions of a panel opening through which said body may extend, said body having communicating openings formed at the juncture of peripheral and rear wall portions thereof at the rear of said marginal flange, a covering plate having a flat outer surface, and a connector-carrying plug, said plate and plug each fitting interchangeably in each of said openings and uniting when one is in one, and the other is in the second of said openings, to close both openings. 20
5. A casing for an instrument of the type described having transversely extending wall portions meeting at an edge of said casing and having an opening in each of said portions which merges at said edge into the opening in the other portion, and having attachment part seats at the margin of said openings, and attachment parts including a tubular instrument connection part, 25 said parts being adapted for mounting in said seats to collectively close said openings with said tubular part extending through either opening. 100
